Primary Examiner — Susan Bennett Hattan*Assistant Examiner* — Leanne Was-Englehart(74) *Attorney, Agent, or Firm* — Ryder, Lu, Mazzeo & Konieczny LLC(57) **CLAIM**

The ornamental design for folding door, as shown and described.

DESCRIPTION

FIG. 1 is a perspective view of the folding door; FIG. 2 is a front view of the folding door of FIG. 1; FIG. 3 is a back view of the folding door of FIG. 1; FIG. 4 is a left view of the folding door of FIG. 1; FIG. 5 is a right view of the folding door of FIG. 1; FIG. 6 is a top view of the folding door of FIG. 1; and, FIG. 7 is a bottom view of the folding door of FIG. 1. The evenly spaced broken lines in the drawings depict environment that forms no part of the claimed design. The dash-dot-dot-dash broken lines in the drawings depict boundary lines. The portion of the design between the boundary lines forms no part of the claimed design.

1 Claim, 5 Drawing Sheets(56)
